UNITED STATES PATENT OFFICE

161,460

AIRPLANE

Alexander Kartveli, Huntington, N. Y., assignor to
 Republic Aviation Corporation, near Farming-
 dale, N. Y., a corporation of Delaware

Application June 11, 1949, Serial No. 3,223

Term of patent 14 years

(Cl. D71—1)

To all whom it may concern:

Be it known that Alexander Kartveli, a citizen of the United States, and a resident of Huntington, in the county of Suffolk and State of New York, has invented a new, original, and ornamental Design for an Airplane, described and claimed in the following specification and shown in the accompanying drawings wherein:

Fig. 1 is a plan view of an airplane embodying the present design;

Fig. 2 is a side elevation thereof;

Fig. 3 is a front elevation thereof; and

Fig. 4 is a perspective view from the front.

What is claimed is:

The ornamental design for an airplane, substantially as shown.

ALEXANDER KARTVELI.
